UNITED STATES PATENT OFFICE.

EDWARD POSSON, OF CHICAGO, ILLINOIS, ASSIGNOR OF ONE-HALF TO FREDERICK C. MAEGLY, OF CHICAGO, ILLINOIS; HARRIS TRUST AND SAVINGS BANK AND EGBERT H. GOLD, EXECUTORS OF SAID EDWARD POSSON, DECEASED, ASSIGNORS OF ONE-HALF TO FAY E. POSSON.

GRAIN DOOR FOR RAILWAY CARS.

Application filed August 16, 1920. Serial No. 404,023.

This invention relates to improvements in grain doors for railway cars and the purpose is to provide an improved sectional grain door.

The principal object of the invention is to provide an improved door which may be applied to any new or old freight car to adapt it for use in shipping grain, although it will be understood that this improved door is of great advantage in the shipment of any kind of freight. A further important object of the invention is to provide a sectional grain door having means for storing the door sections in an improved manner within the car. Still another object is to provide a door comprising a plurality of complementary sections which are movable in guideways and permanently attached to the car structure so that they cannot be removed by unauthorized persons. Still another object is to provide means for permitting the ready removal of the door sections for purposes of replacement or repair. Another improved feature is the provision of means for insuring the movement of the several door sections in the proper directions from the door opening into the supporting guideways in which they are stored. Other objects relate to various features of construction and arrangement to insure safety and dispatch in operation which will appear more clearly hereinafter.

The nature of the invention will be understood from the following specification taken with the accompanying drawings in which one embodiment is illustrated.

In the drawings—

Figure 1 shows a longitudinal sectional view through a railway car having the present invention applied thereto, the door sections being illustrated in door closing position;

Fig. 2 shows a longitudinal sectional view, similar to Fig. 1, with the complementary door sections stored in their guideways on the side walls of the car;

Fig. 3 shows an enlarged longitudinal sectional view, similar to Fig. 2, showing one of the door sections in its initial position passing from the door opening toward the end of the car;

Fig. 4 shows a perspective view of the outer side of one of the door sections, illus-

trating the construction of the lugs by which the door sections are connected to the guideways;

Fig. 5 is a view similar to Fig. 4 showing a perforated door section which may be used for ventilating purposes;

Fig. 6 shows a longitudinal sectional view on the line 6—6 of Fig. 3;

Fig. 7 shows a detail perspective view of the lower left hand corner of the door opening, illustrating the means for guiding the lower edges of the lower door sections against the door post, and the means for permitting the escape of grain from the lower end of the guideway;

Fig. 8 is a horizontal sectional view similar to that of Fig. 6, showing a modified form of construction;

Fig. 9 shows an enlarged vertical section on the line 9—9 of Fig. 3;

Fig. 10 shows a detail view of the upper left hand corner of the car, as viewed in Fig. 2, illustrating the method of removing the door sections from the guideways;

Fig. 11 shows an enlarged perspective view of the upper left hand corner of the door opening, as viewed in Fig. 2, illustrating the construction of the guideways and the means for preventing the accidental return of the door sections to positions over the door opening; and

Fig. 12 shows a perspective view of the inner side of one of the pivoted latches, illustrated in Figs. 1, 2 and 11.

The railway car illustrated in the drawings comprises a floor 15, end walls 16, a roof 17 and side walls 18. Each side wall 18 is provided with a door opening 19 which is bounded along its lateral sides by the door posts 20 and along its upper edge by the upper door sill 21. The lower door sill 22 extends between the door posts, as shown particularly in Fig. 6. The door opening 19 is adapted to be closed by a plurality of complementary door sections 25 which extend across the door opening and overlap the inner sides of the door posts. These door sections are preferably formed of wooden fillers 26, covered by sheet metal 27, as illustrated in Fig. 9, in order to provide a combination of strength and light weight. The longitudinal edges of the door sections 105 are provided with interfitting flanges 28 and

notches 29, whereby a grain tight closure is formed between the sections when they are in the position illustrated in Fig. 1. The door sections are further provided with indentations 30 which form hand holds to permit the lifting of the door sections by the operator. Another centrally located indentation 31 is provided near the lower edge of each door section which is capable of occupying the lowermost position in the door opening in order to permit the operator to pry the sections upwardly by means of a crowbar. Each door section is provided on its inner side with three projecting lugs 32 which extend through and are riveted to the door sections, as illustrated in Fig. 9. These lugs have reduced necks 32^a and enlarged heads 32^b and these lugs are adapted to travel in guideways 33 which extend vertically along the inner sides of the door posts. These guideways are formed by means of spaced metal strips or plates 34 which are seated on and secured to the wooden cleats 35 and 36 carried by the inner surfaces of the door post and the metal plates overlap the edges of the wooden cleats and the heads of the lugs 32 so that the door sections are securely attached to the guideways and are capable of vertical movement only therein. In order to permit the outward flow into the interior of the car of any grain which may enter the guideways 33, the lower extremities of the inner cleat 36 and the metal guide plate 34 which is carried thereby, are terminated a short distance above the floor 15 of the car, as shown at 38. A metal plate 39 is secured to the floor adjacent each door post, as shown in Figs. 6 and 7, and these metal plates are provided with slightly inclined faces 39^a adapted to engage the lowermost part of the door section so that the door section is forced tightly against the lower edge of the door post in order to prevent any leakage of grain at this point.

An important feature of the invention is the location of the guiding lugs 32. Two of these lugs are located adjacent the upper and lower corners of one end of each door section and the other lug is located adjacent the upper corner of the other end of the section, as shown particularly in Figs. 3 and 4. The two lugs at one end of each door section travel in one of the guideways 33 and the other lug at the other end of the section travels in the other guideway 33 during the vertical movement of the door section. Any number of door sections may be provided but in the embodiment illustrated in the drawings there are four door sections, and the lugs 32 on two of these door sections are arranged opposite to the manner of arrangement of the lugs on the other two sections for a purpose hereinafter described.

In order to protect the movable door sections 25 from damage by the movement of boxes or other lading within the car, a protecting member or door jamb 37 is provided along each lateral edge of the door. Each 70 protecting member 37 is secured to the side wall of the car by bolts 37^a and the edge thereof toward the end of the car is curved, as shown at 37^c, in order to permit articles within the car to slide thereover. The member 37 is notched out along its inner edge, as shown at 37^b, to permit it to extend over the member 36 which forms the outer wall of each vertical guideway 33, as shown in Fig. 6. A metal plate 37^c is preferably secured to each of the members 37 with the edge thereof projecting beyond the edge of the protecting member and overlapping the end of the door section which is notched out or recessed, as shown at 37^d, to receive the projecting portions of the plate. The outer surface of each member 37 is recessed to receive the plate 37^c so that the surface of the plate forms a continuation of the curved surface 37^c and the plates are adapted 85 to lie flush with the inner surfaces of the door sections so that the movement of the lading within the car will not cause any injury to the door sections. The members 37 and 37^c form auxiliary guideways for directing the door sections in their vertical travel and these guideways serve to increase the effectiveness of the door sections in providing a grain tight closure. The members 37 and 37^c are extended upwardly to a height corresponding to the upper edge of the uppermost door section when the door sections are in their door closing positions, as shown in Fig. 1, and the door jambs 37 are preferably spaced from the ends of the 90 door sections 25 sufficiently to prevent the binding of the door sections between them. This may preferably be accomplished by proportioning the parts so that the guiding lugs will engage the walls of their guideways before the ends of the door sections engage the members 34, even when the door sections are tilted.

A modified form of this construction is illustrated in Fig. 8 where a wooden door jamb 37^d is secured to the side of the car wall by means of bolts 37^e. This construction is similar to that illustrated in Fig. 6 except that the wooden door jamb 37^d is used alone without a metal plate overlapping the ends of the door sections, although the surface of the door jamb 37^d is adapted to lie flush with the inner surfaces of the door sections, as shown in the preferred form of construction.

The door sections are adapted to be stored adjacent the roof of the car and along the side walls on parallel longitudinal guideways 40 and 41. Each upper guideway 40 extends substantially throughout the length 130

of the car and above the door opening, but the lower guideway is formed in two parts which terminate at the door posts where they communicate with the vertical guideways 33.

- 5 The upper guideways 40 are formed by metal guide-plates 44 which are secured in recesses formed in the wooden supporting members 45, arranged longitudinally of the car and supported by the usual side wall posts 46 and braces 47. If desired, additional frame members may be attached to the side walls of the car. The metal plates 44 extend inwardly and overlap the heads of the lugs 32, as shown in Fig. 9. The two parts 10 of lower guideway 41 are formed by other metal guide plates 49 which are secured to longitudinal frame members 50 also carried by the posts 46 and braces 47. The lower guideway 41 has only one plate 49 which extends upwardly and overlaps the head of the lower lug 32 but the removal of the door sections from the guideways will be prevented by the two plates 44 of the upper guideway and the engagement of the plate 49 with the 15 single lower lug 32 serves to prevent the door section from swinging outwardly at its lower edge away from the wall of the car. It will be observed that the guideways are located near the roof above the inside 20 sheathing 51 of the car so that when the door sections are in their upper positions, as illustrated in Fig. 2, they do not interfere with or damage the lading within the car nor are the doors damaged by the lading 25 which does not require side door protection. The vertical guideways 33 communicate with the upper guideways 40, as shown at 53, and a communication is also provided between the vertical guideways 33 and the lower guideways 41 by means of openings 54, which are formed in the metal plates 44 and the cleats 36 on the sides of the guideways 33 nearest to the ends of the car. The metal 30 guide plates 34 and 44 which bound the inner sides of the guideways 33 and 40 around the door opening are continuous, as shown particularly in Fig. 3.

When a door section is moved vertically until it reaches the upper limit of its travel, 35 it may be moved in one direction longitudinally of the car by passing the upper lugs 32 along the upper guideways 40 and by passing the single lower lug 32 through one of the openings 54 into engagement with one of the lower guideways 41. The use of two guiding lugs 32 at one end of the section, and only one lug 32 at the other end will permit the movement of each door section 40 in one direction only longitudinally of the car, since it is necessary to pass each of the lugs 32 at the lower corner of the door section through one of the openings 54, and the movement thereof in the opposite direction 45 is prevented by the opposite vertical wall of the guideway 33. The direction in which the

door section should be moved can be readily ascertained after it has reached the upper limit of its travel in the vertical guideways, but to facilitate the ready movement of the door sections in the proper directions, arrows 70 are preferably painted on them, as shown at 55.

If two of the door sections have been moved longitudinally in one direction and the other two door sections have been moved 75 longitudinally in the other direction, they will occupy the positions illustrated in Fig. 2, and to prevent the unauthorized removal of the sections from the horizontal guideways, metal cleats 58 are placed across the 80 extremities of the upper guideways 40 and 41 and riveted or bolted thereto. These plates 58 also serve as stops to limit the end-wise movement of the door sections. The plate 44 and frame member 45 which form 85 the lower wall of each upper guideway 40 are extended beyond the plate 44 and frame member 45 which form the upper boundary of the guideway, adjacent the end wall of the car, as shown at 59, and both of these plates 90 44 are extended beyond the end of the lower guideway 41 which terminates some distance from the end wall of the car, as shown at 60. With this construction, the plates 58 may be removed by authorized persons by removing 95 the bolts or rivets and then the door sections 25 may be removed from the guideways by following the movement illustrated in Fig. 10. The door section 25 is first extended longitudinally until the lug 32 at the upper corner thereof and nearest the end of the car passes beyond the extremity of the upper wall of the guideway 41. At the same time the lower lug 32 will have passed beyond the extremity 60 of the lower guideway. The 105 end of the door section adjacent the end wall of the car can then be elevated to pass the upper lug 32 out of engagement with the lower wall of the upper guideway 41 and the door section can then be swung or tilted 110 downwardly into the position 25^a. The door section can then be moved longitudinally into the position 25^b and thus pass the single lug at the upper end thereof beyond the extremity of the upper wall of the upper guideway. The entire door section can then be lifted off of the upper guideway and thereby separated from the car. The door sections are replaced by reversing the operation 115 just described.

In order to prevent the accidental return of the door sections to the vertical guideways 33, it is desirable to provide latch members 65 which are pivoted at 66 on the plates 67 carried by the upper frame members 45 adjacent the upper corners of the door opening. These latch members are provided with inclined shoulders 68 on their inner sides, which shoulders are adapted to rest upon the upper edges of the upper plates 44 and 120 125 126

thus hold the latch members normally in the inclined positions illustrated in Fig. 1. When a door section is moved upwardly in the vertical guideways and thence longitudinally therefrom in the horizontal guideways, the latch member toward which the door section is moved, is automatically lifted by engagement with the door section and rides thereon, as illustrated in Fig. 3. After the door sections have passed, the latch member drops into the position illustrated in Fig. 11 and automatically holds the door sections against return movement.

During the opening movement of a door section, the single lug 32 at the upper corner of the trailing end of the door section has a tendency to drop into the vertical guideway 33 at the opposite edge of the door opening and, to prevent this dropping movement, supporting plates 70 are provided adjacent the opposite edges of the door opening. These plates are secured to the lower frame members 50 by means of bolts 71 and although there is preferably a slight clearance between these blocks and the lower edges of the door sections, they will effectively prevent the dropping of the lugs 32 into the wrong vertical guideways.

A further important feature of the invention is the provision of safety stops 75 which are pivoted on bolts 76 engaging the opposite door posts 20. These stop members 75 are provided with curved slots 77 which are engaged by pins 78 secured in the door posts. These pins hold the stop members normally in upwardly directed inclined positions with the ends thereof projected beyond the guideways 33 to engage the lower edges of a door section a short distance below the lower guideways 41. These stop members will engage and hold a single door section when it drops into the guideways 33 and they serve to prevent injury to a person who might be located in the doorway without notice of the movement of the door section. These latch members can be readily elevated by hand at the same time that the door sections are being manipulated in order to permit the lowering of the latter. When the door sections are elevated they will automatically push the stop members 75 outwardly and the manual movement of them is unnecessary.

Instead of employing solid door sections of the kind heretofore described for adapting the car for use in shipping grain, these solid door sections may be removed and replaced by other complementary door sections comprising metallic frame members 81 of channel form inclosing sheets of relatively stiff woven wire. Plates 83 are secured in the corners of each frame and three of these plates are provided with projecting lugs 84 corresponding to the lugs 32. The lugs 84 are adapted to engage the guideways 33, 40 and 41 and by the use of these door sections,

the car can be employed for shipping fruit or vegetables. When using either the solid or the perforated door sections, they can be locked in a position to close the door opening by connecting them together in pairs by means of plates 85 and 85^a and padlocks 86. Since only one door section can be removed into the horizontal guideways at a time, the locking of two of them together will effectively prevent the removal of any of them from the door opening.

The use of three connecting lugs 32 on each door section serves to secure the door sections in close relation to the guideways so that the lower portions thereof cannot swing outwardly away from the door opening or from the side walls of the car. This construction also makes it possible to hold the door sections in proper relation to the car wall without the necessity of forming any openings in the vertical guideways 33, which openings might possibly permit the unauthorized detachment of the door sections.

The plates, which are secured to the floor of the car for engaging the lowermost door section, are adapted to hold this section against the door posts and guideways so that the leakage of grain adjacent the bottom of the car is effectively prevented. Any number of door sections may be used in order to close any part or all of the door opening, and by shifting the door sections longitudinally of the car in both directions from the door opening it is possible to keep the door sections as close as possible to the roof of the car when they are not in use so that they do not interfere with the freight within the car. Since the door sections fit tightly against the side wall when they are stored in the horizontal guideways, they are not readily put out of commission by the freight in the car and they are adapted for use with substantially any kind of freight. The improvement can be applied to substantially

any new or old car without taking any space from the doorway or without occupying any material portion of the space within the car. The sections are relatively light and are practically indestructible. A distinctive advantage of the invention is that the door sections cannot be removed from the car except by authorized persons for purposes of replacement or repair, and this removal is effectively accomplished in the manner heretofore described. When the sections are stored in the horizontal guideways, they are prevented from accidentally returning to the vertical guideways by pivoted latches, and the dropping of the trailing end of a door section into one of the vertical guideways during the movement of the door away from the door opening, or of the leading end during the closing movement, is prevented by the fixed lugs which are adapted to engage

the undersides of the door sections adjacent the

the door posts. A further precaution against the accidental dropping of the door sections into the vertical guideways is taken through the provision of the pivoted latches 75 which catch each door section before it has dropped very far from the horizontal guideways. These latches can be conveniently elevated by one operator when the door sections are being lowered. In elevating the door sections they can be moved only in one direction and this direction can be determined by trial or by inspection of the arrows marked on them. The use of three connecting lugs engaging the guideways is 10 effective in preventing any objectionable binding of the door sections in the vertical guideways and such binding as does occur, takes place between the lugs located at the diagonally opposite corners of the door sections 15 when these sections engage the metal plates which form the walls of the guideways adjacent the door opening. The binding action therefore puts the door section under tension diagonally and with this arrangement it is found that the door section 20 quickly releases itself and that no permanent binding takes place.

Although I have explained certain embodiments and uses of the invention, it will 25 be understood that various changes may be made without departing from the scope of the appended claims.

I claim:

1. The combination in a railway car having 30 a door opening in its wall of a plurality of complementary door sections, means for guiding said sections successively to the upper part of said door opening, means for guiding some of said sections in one direction only from the upper part of said door opening longitudinally of the car, and means for guiding the other sections in the other direction only from the upper part of said door opening longitudinally of the car.

45 2. The combination in a railway car having a door opening in its wall of a plurality of complementary door sections, of vertical guideways extending along the lateral edges of said door opening, horizontal guideways 50 communicating with the upper parts of said vertical guideways and extending longitudinally of the car in both directions, and means carried by said door sections and engaging said guideways for permitting some 55 of said door sections to move in one direction only in said horizontal guideways and to permit the other door sections to move in the other direction only in said horizontal guideways.

60 3. The combination in a railway car having a door opening in its wall, of vertical guideways extending along the lateral edges of said door opening, a horizontal guideway extending over said door opening and longitudinally of the car in both directions there-

from, other horizontal guideways located below and parallel to said first-named horizontal guideway, said horizontal guideways communicating with said vertical guideways, a plurality of complementary door sections, 70 a pair of lugs carried by one end of each door section to engage said upper guideway and one of said lower guideways, and a single lug carried by the other end of each door section and adapted to engage said 75 upper guideway, the lugs at both ends of each door section being adapted to engage said vertical guideways.

4. The combination in a railway car having a door opening in its wall of vertical 80 guideways extending along the lateral edges of said door opening, upper and lower horizontal guideways extending longitudinally of said car along its wall, said upper guideway communicating with both of said vertical guideways, said lower guideways communicating with one of said vertical guideways only, a plurality of complementary door sections, a pair of lugs secured to one end of each door section to engage said 85 vertical guideways and said upper and lower guideways, and a single lug secured to the other end of each door section to engage the other vertical guideway and the upper horizontal guideway only.

5. The combination in a railway car having a door opening in its wall of a plurality of complementary door sections, vertical guideways extending along the lateral edges of said door opening, an upper guideway 100 communicating with both of said vertical guideways and extending longitudinally of the car therefrom, lugs secured to said door sections and engaging said guideways, and means carried by the car wall adjacent one of said vertical guideways for preventing the lug at the trailing end of each door section during its opening movement from dropping into the vertical guideway adjacent said lug.

6. The combination in a railway car having a door opening in its wall of a plurality of complementary door sections, vertical guideways extending along the lateral edges of said vertical guideways, upper and lower horizontal guideways extending longitudinally of the car from said vertical guideways and terminating adjacent the end walls of the car, said upper guideway communicating with both vertical guideways, said lower guideway communicating with one vertical guideway only, lugs secured to said door sections and engaging said guideways to permit the upward movement of said door sections in said vertical guideways and the longitudinal movement thereof in said upper and lower guideways, the end of each door section near the end wall of the car toward which it moves being provided with lugs 115 to engage both the upper and lower guide- 120 125 130 135 140 145 150 155 160 165 170 175 180 185 190 195 200 205 210 215 220 225 230 235 240 245 250 255 260 265 270 275 280 285 290 295 300 305 310 ways, the other end of each door section being provided only with a lug adapted to engage the upper guideway.

7. The combination in a railway car having a door opening in its wall of a plurality of complementary door sections, vertical guideways extending along the lateral edges of said door opening, horizontal guideways communicating with the upper parts of said vertical guideways and extending longitudinally of the car, lugs secured to said door sections and slidably engaging said guideways, and means detachably secured to the ends of said horizontal guideways for permitting the removal of said lugs from said guideways adjacent the end of the car.

8. The combination in a railway car having a door opening in its wall of a plurality of complementary door sections, vertical guideways extending along the lateral edges of said door opening, a horizontal guideway extending longitudinally of the car along its side wall and communicating with both of said vertical guideways, lugs secured to said door sections and adapted to travel in said guideway, said horizontal guideway comprising upper and lower guide members spaced apart and adapted to overlap parts of said lugs, the lower guide member of said horizontal guideway extending beyond the upper guide member thereof, and means detachably secured across said horizontal guideway adjacent its extremities for preventing the removal of said lugs from said guideway.

9. The combination in a railway car having a door opening in its wall of a plurality of complementary door sections, vertical guideways extending along the lateral edges of said door opening, upper and lower horizontal guideways extending longitudinally of the car from said vertical guideways and terminating adjacent the end wall of the car, said upper guideway communicating with both vertical guideways, said lower guideway communicating with one vertical guideway only, lugs secured to said door sections and engaging said guideways to permit the upward movement of said door sections in said vertical guideways and the longitudinal movement thereof in said upper and lower guideways, the end of each door section near the end wall of the car toward which it moves being provided with lugs to engage both the upper and lower guideways, the other end of each door section being provided with a lug adapted to engage the upper guideway only, said upper guideway extending beyond said lower guideway, and means detachably secured across said upper guideway to prevent the removal of said lugs from the end thereof.

10. The combination in a railway car having a door opening in its wall of a plu-

rality of complementary door sections, vertical guideways extending along the lateral edges of said door opening, upper and lower horizontal guideways extending longitudinally of the car from said vertical guideways and terminating adjacent the end wall of the car, said upper guideway communicating with both vertical guideways, said lower guideway communicating with one vertical guideway only, lugs secured to said door sections and engaging said guideways to permit the upward movement of said door sections in said vertical guideways and the longitudinal movement thereof in said upper and lower guideways, the end of each door section near the end wall of the car toward which it moves being provided with lugs to engage both the upper and lower guideways, the other end of each door section being provided with a lug adapted to engage the upper guideway only, said upper guideway comprising guide members spaced apart and adapted to overlap parts of said lugs, said lower guideway comprising a guide member underlying said lugs and overlapping parts thereof, said upper guideway extending beyond said lower guideway.

11. The combination in a railway car having a door opening in its wall of a plurality of complementary door sections, vertical guideways extending along the lateral edges of said door opening, upper and lower horizontal guideways extending longitudinally of the car from said vertical guideways and terminating adjacent the end wall of the car, said upper guideway communicating with both vertical guideways, said lower guideway communicating with one vertical guideway only, lugs secured to said door sections and engaging said guideways to permit the upward movement of said door sections in said vertical guideways and the longitudinal movement thereof in said upper and lower guideways, the end of each door section near the end wall of the car toward which it moves being provided with lugs to engage both the upper and lower guideways, the other end of each door section being provided with a lug adapted to engage the upper guideway only, said upper guideway comprising guide members spaced apart and adapted to overlap parts of said lugs, said lower guideway comprising a guide member underlying said lugs and overlapping parts thereof, said upper guideway extending beyond said lower guideway, the lower guide member of said upper guideway extending beyond the upper guide member thereof, and means detachably secured across said upper guideway for preventing the removal of said lugs from the end thereof.

In testimony whereof, I have subscribed my name.

EDWARD POSSON.
